UNITED STATES PATENT OFFICE.

PHILIPP HAKE, OF HOBOKEN, NEW JERSEY.

DESIGN FOR VISITING-CARDS.

SPECIFICATION forming part of Design No. 11,604, dated January 13, 1880.

Application filed November 17, 1879. Term of patent 7 years.

To all whom it may concern:

Be it known that I, PHILIPP HAKE, of Hoboken, in the county of Hudson and State of New Jersey, have invented a new and original 5 Design for a Visiting-Card, of which the following is a specification.

The accompanying drawing represents a face view and an end view of a visiting-card embodying my design.

10 This invention relates to a new ornamentation of the edges of a visiting-card; and it consists in a new design applied to the beveled edges of such a card.

15 The card A has beveled edges *a* along its entire contour, which edges are, by preference,

gilt or silvered. Transverse parallel lines are formed on said beveled edges, thereby imparting to them a peculiar appearance, each line being at right angles with the edges of the bevel in which it is placed. 20

I claim—

The design for the card A, which consists of series of lines placed on the beveled edges thereof, each line being at right angles to the edges of the bevel in which it is placed, substantially as shown. 25

PHILIPP HAKE.
